UNITED STATES PATENT OFFICE

FREDERICK WEHINGER, OF WATERBURY, CONNECTICUT, ASSIGNOR TO WATERBURY CLOCK COMPANY, OF WATERBURY, CONNECTICUT, A CORPORATION

ALARM CLOCK

Application filed December 26, 1929. Serial No. 416,849.

My invention relates to an improvement in alarm clocks, the object being to produce a simple, reliable and convenient mechanism therefor, designed to sound a relatively-
5 brief warning-alarm, and, at the termination of a predetermined interval thereafter, the final or full-alarm.

With these ends in view, my invention consists in an alarm-mechanism having certain details of construction and combinations of parts as will be hereinafter described and pointed out in the claims.

In the accompanying drawings:

Fig. 1 is a view in rear elevation of an alarm-clock embodying my invention;

Fig. 2 is a view in front elevation of the movement and bell thereof as detached from the clock-case;

Fig. 3 is a broken view in vertical transverse section on the line 3—3 of Fig. 2, showing the short warning-alarm control-pin engaged with the control-slide;

Fig. 4 is a corresponding view but showing the parts in the positions due them after the sounding of the warning-alarm and before the sounding of the full-alarm with the long full-alarm control-pin engaged with the control-slide;

Fig. 5 is a detached perspective view of the alarm-cam wheel and its double alarm-cam;

Fig. 6 is a similar view of the alarm-escapement wheel;

Fig. 7 is a detached perspective view of the alarm-control slide;

Fig. 8 is a similar view of the alarm-cam spring;

Fig. 9 is a similar view of the alarm-shut-off lever;

Fig. 10 is a detached inside view of the alarm-bell showing the alarm-muffler lever and the alarm-muffler plate carried thereby;

Fig. 11 is a detached perspective view of the alarm-muffler lever and the muffler-plate carried by it.

In carrying out my invention as herein shown, I employ a sleeve-like alarm-cam 15 carried by and concentric with an alarm-cam wheel 16 and having its outer edge shaped 50 to provide a warning-alarm drop 17, a short

warning-alarm dwell 18 and a full-alarm drop 19 directly beneath which is the low-point 20 of the cam-rise 21 which merges at about the point 22 into a relatively-long dwell 23 which terminates at the warning-alarm drop 17 aforesaid. As thus constructed, the alarm-cam 15, though but a single element, operates as a double cam, the drop from its long dwell 23 to the start 20 of the rise 21 being divided into two stages by the short warning-alarm dwell 18. The alarm-cam as thus constructed is operated by an alarm-cam finger 24 projecting radially from a collect 25 staked upon the forward end of an alarm-set-staff 26 having bearing near its forward and rear ends, respectively, in the front and back plates 27 and 28 of the clock-movement and provided at its projecting rear end with a finger-button 29 by which the staff is turned for "setting the alarm." The alarm-wheel 16 is mounted, as usual, upon the forward end of the alarm-set-staff 26 with freedom for rotary and axial sliding movement thereupon and, as common in alarm clocks, it meshes into the minute-pinion 30 of the usual dial-work of the time-trains of such clocks.

The axial movement upon the staff 26 of the alarm-wheel 16 and hence of the alarm-cam 15 is provided for, as usual, by a flat sheet-metal alarm-cam-spring 31 secured at its outer end by a screw 32 to the front movement-plate 27 and having an elongated clearance-opening 33 through which the staff 26 passes. This spring, as common in such alarm-mechanisms, engages with the inner face of the alarm-wheel 16 and exerts a constant effort to move the same and the double alarm-cam 15 axially outward upon the staff 26 so as to maintain the shaped outer edge of the cam in constant engagement with the alarm cam-finger 24 aforesaid.

At its free end the spring 31 is formed with a rectangular notch 34 producing complementary fingers 35 respectively entering notches 36 in the opposite edges of a flat sheet-metal rectangular alarm-control slide 37 bearing at its outer end in a slot 38 in an arm 39 offset from a bracket 40 secured by screws 41 to the front movement-plate 100

27. At its inner end the said control-slide 37 has bearing in a slot 42 in the said front movement-plate. The control-slide as thus constructed and mounted has rectilinear movement in a plane parallel with the axis of the clock-movement, its projecting inner end alternately co-acting with a short warning-alarm control-pin 43, and a longer full-alarm control-pin 44. Both of the pins are carried by and project forwardly from an alarm-escapement wheel 45 also carrying a rearwardly-projecting alarm-shut-off pin 46. The alarm-escapement wheel 45 co-acts, as usual, with a verge 47 on an oscillating verge-shaft 48 mounting a hammer-arm 49 carrying a hammer 50 located adjacent to the inner face of the flange 51 of the bell 52.

28. The alarm-shut-off pin 46 aforesaid acts with the stop-tooth 53 of an alarm-shut-off lever 54 pivotally hung between its ends upon a pivot 55 in the front movement-plate 27. At its upper end the said lever is bent rearwardly to form an operating-finger 56 projecting through a slot 57 (Fig. 1) in the back 58 of the clock-case 59, so as to be available for manual manipulation by the user of the clock. At its lower end the said lever is provided with a rearwardly-turned operating-finger 60 positioned for engagement by the outermost convolution of the alarm-spring 61 for the automatic operation of the lever, so that, in case the lever is not manually operated for shutting off 35 the full-alarm, the same will be ultimately shut off by the alarm-spring as it expands into engagement with the said finger 60 as the alarm-train runs down, whereby the lever is rocked on the pivot 55 to bring its stop-tooth 53 into the path of the alarm-stop-pin 46.

To suit the tastes of individual users of the clock, I provide means for regulating the volume of sound from the maximum, to 45 the minimum that will answer the purpose. For this purpose I locate within the bell (Figs. 10 and 11) an alarm-muffler lever 62 hung at its inner end on a pivot 63 and at its outer end carrying an alarm-muffler plate 59 64 furnished with a fastening-arm 65 by which it is secured by rivets 66 to the free end of the lever, the plate 64 being positioned to lie alongside the inner face of the flange 51 of the bell but not concentric therewith. An operating-arm 67, secured to the outer end of the lever 62, passes rearwardly through a clearance-slot 68 (Fig. 1) in the back 58 of the clock-case 59. By means of this operating-arm the muffler-plate 64 may 65 be cleared entirely from the bell-hammer 50 which is then free to impinge directly upon the flange of the bell so as to produce the maximum volume of noise. As the lever 67 is moved upward by its operating-handle 69, the end of the muffler-plate 64 is ad-

vanced at an angle between the bell-hammer 50 and the bell-flange 51, whereby the distance between the hammer and flange is progressively increased with the effect of correspondingly decreasing the effective force of the hammer upon the bell-flange and correspondingly reducing the volume of the sound, since the impact of the hammer is then transmitted through the muffler-plate and a progressively-longer section thereof. 70

The other details of the clock chosen for the illustration of my invention may follow approved practice and do not call for detailed description.

Coming now to the operation of my improved alarm-mechanism, let it be assumed that the parts thereof are in their normal positions (Figs. 2 and 3), the shut-off lever 54 being in its retired position and the inner end of the control-slide 37 being engaged by the short warning-alarm control-pin 43. Now in the running of the time-train of the clock, the alarm-cam wheel 16 is rotated and hence the double alarm-cam 15 beneath the cam-finger 24 on the alarm-set-staff 26. As soon in the rotation of the cam 15 as the warning-alarm drop 17 passes fully from under the cam-finger 24, the alarm-cam wheel 16 and the alarm-cam 15 will be snapped axially forward on the staff 26 by the alarm-cam-spring 31 until the short warning-alarm dwell 18 is brought into engagement (Fig. 4) with the rear face of the said finger 24, whereby the control-slide 37 is moved outwardly sufficiently to disengage its inner end from the short warning-alarm control-pin 43, releasing the escapement-wheel 45 to the action of the alarm-spring 61, for clockwise rotation until the full-alarm control-pin 44 is brought into engagement with the now partially-retired control-slide 37. The parts of the mechanism now occupy the positions in which they are shown in Fig. 4. During this interval, in which a partial rotation only of the escapement-wheel 45 takes place, a warning-alarm of short duration is sounded. 100

The continued rotation, under the action of the time-train, of the alarm-wheel 16 and the alarm-cam 15, gradually moves the short warning-alarm dwell 18 out from under the alarm-cam finger 24 sufficiently to clear the full-alarm-drop 19 from it, whereupon the spring 31 acts to move the wheel 16 and cam 15 further outward until the start 20 of the cam-rise 21 is engaged with the inner face of the alarm-cam finger 24. Concurrently with the action above described, the spring 31 has moved the alarm-control slide 37 to the limit of its outward movement, in which its inner end is disengaged from the long full-alarm control-pin 44. 115

The alarm-train is thus again released, permitting the alarm-escapement wheel 45 to continuously rotate clockwise until the 120

user of the clock manually moves the shut-off lever 54 by its operating-finger 56 to bring the shut-off tooth 53 of the lever into the path of the stop-pin 46 projecting rearwardly from the escapement-wheel 45, or until the expansion of the alarm-spring 61, acting through the finger 60 of the shut-off lever 54, automatically acts to rock the lever 54 and swing its tooth 53 into the path of the said stop-pin 46.

It may now be noted that the pins 43 and 44, carried by the escapement-wheel 45, are so positioned relatively to each other and to the pin 46 that when the latter is engaged with the nose 53 of the shut-off lever 54, the short warning-alarm control-pin 43 will be in position to engage with the inner end of the control-slide 37 when the shut-off lever is manually operated to disengage its tooth 53 from the pin 46, so that the parts will be left in readiness to sound the warning-full-alarms in proper sequence, when the actuation of the time-train automatically releases the alarm-train.

Now in the running of the time-train of the clock, the rise 21 of the cam will slowly ride under the alarm-cam finger 24 and push the alarm-wheel 16 and its cam 15 axially inward on the staff 26 against the tension of the spring 31, whereby the alarm-control slide 37 will be moved inward sufficiently to enter the path of the short warning-alarm control-pin 43 to be engaged thereby as soon as the shut-off lever has been swung into its retired position.

In the continued running of the time-train, the long dwell 23 of the double alarm-cam 15 slowly rides under the alarm-cam finger 24 until the warning-alarm drop 17 passes fully from under the finger 24, after which the cycle of operations already rehearsed is repeated.

I claim:

1. In an alarm clock for sounding a warning-alarm followed at a predetermined interval by a full-alarm, the combination with the time- and alarm-trains thereof, of an alarm-control slide limited to rectilinear movement and engageable with a running part of the said alarm-train, means for positively guiding said slide into and out of position for engagement with said part and for supporting same when engaged by said part, and means controlled by the said time-train for causing the said control-slide to retire in a two-step movement.

2. In an alarm clock for sounding a warning-alarm followed at a predetermined interval by a full-alarm, the combination with the time- and alarm-trains thereof, of a two-drop alarm-cam driven by the said time-train, an alarm-cam spring, an alarm-control slide limited to rectilinear movement and engageable with a running part of the said alarm-train and connected to the said alarm-

spring for being retired thereby in two stages under the control of the said two-drop alarm-cam, and means for positively guiding said slide in its movement under the influence of said spring and for supporting it when engaged by said running part.

3. In an alarm clock for sounding a warning-alarm followed at a predetermined interval by a full-alarm, the combination with the time- and alarm-trains thereof, of a pair of complementary abutments carried by a rotating member of the said alarm-train; an alarm-control slide limited to rectilinear movement and adapted to be interposed by stages in the path of the two said control-abutments; means for positively guiding and supporting said slide, and means driven by the said time-train for successively disengaging the said slide from the shorter and longer of the two control-abutments to permit the alarm-train to sound a warning-alarm at a predetermined time before the sounding of the full-alarm.

4. In an alarm clock for sounding a warning-alarm followed at a predetermined interval by a full-alarm, the combination with the time- and alarm-trains thereof, of a reciprocating control-slide engageable with a running part of the said alarm-train, guide-means for the said control-slide constructed and arranged to guide the same in a rectilinear path, an alarm-cam spring connected to the said control-slide for moving the same, and an alarm-cam acting through the said alarm-cam spring and contoured to effect the retirement of the said control-slide to release the alarm-train on two occasions to permit the same to sound a warning-alarm and a full-alarm at a predetermined interval thereafter.

In testimony whereof, I have signed this specification.

FREDERICK WEHINGER.
